J. A. LARMORE.
CAR COUPLING.
APPLICATION FILED JUNE 9, 1916.

Patented May 15, 1917.

FIG.1.

FIG.2.

FIG.3.

WITNESS:

Robt R. Kitchel.

INVENTOR

James A. Larmore
BY Frank J. Busser

ATTORNEY.

UNITED STATES PATENT OFFICE.

JAMES A. LARMORE, OF WESTGROVE, PENNSYLVANIA.

CAR-COUPING.

1,226,085.

Specification of Letters Patent. Patented May 15, 1917.

Application filed June 9, 1916. Serial No. 102,607.

To all whom it may concern:

Be it known that I, JAMES A. LARMORE, a citizen of the United States, residing at Westgrove, county of Chester, and State of Pennsylvania, have invented a new and useful Improvement in Car-Couplings, of which the following is a full, clear, and exact description, reference being had to the accompanying drawings, which form a part 0 of this specification.

My invention relates to the class of car couplers generally known as of the "Janney" type, whereby cars provided with them may be coupled together by the impact of 15 coming together and without the aid of an operator. In this coupler, in general, a knuckle jaw is held in coupled position by a latch which may be sprung to accomplish the uncoupling.

20 The principal object of my invention is to provide a coupler combining these features in a novel and advantageous manner. To this end I provide in the drawhead a knuckle jaw and a latch lever, and spring 25 connection between the two which is always active, no matter in what position the knuckle may be.

My coupler will act to engage with another mating coupler when the knuckle jaws 30 of both are open or when one is open and the other closed. I am aware that this is not a new accomplishment, *per se*, but I accomplish it by a very simple construction, necessitating only the parts above named, 35 and therefore insuring a maximum of dependability and length of life at a minimum cost.

My invention has certain other features of novelty and advantage, which will be 40 brought out in the description.

I will now proceed to describe in detail a preferred embodiment of my invention in connection with the accompanying drawings, in which—

45 Figure 1 is a horizontal view, partly broken away, of two of my improved couplers in engaged relation.

Fig. 2 is a similar view showing the couplers in the act of disengaging, one of 50 the knuckles having been sprung open.

Fig. 3 is a similar view showing the couplers about to engage each other, both knuckles being in open position.

a, a' represent the drawheads of the op-

posing cars provided with my improved 55 couplers.

The drawheads are of the usual circular shape, and each contains the knuckle jaw *b*, pivoted at *c*. Pivoted directly to the rear of pivot *c* is the latch lever *d* having the 60 rearwardly extending arm *e*. As shown, this arm may be connected with a rod *f* extending to the side of the car for convenience of operating.

The other arm of lever *d* carries a block 65 pivoted at *g* through which slides a rod *h* pivoted to the knuckle jaw *b*. This rod carries a coiled spring *i* always in compression between the lever and the knuckle jaw.

Lever *d* is provided with a notch *j* which 70 engages the tail of the knuckle jaw when the latter is in its closed position, as shown in Fig. 1 and in the right hand coupler in Fig. 2.

In order to engage the jaws and couple 75 the cars when the couplers are brought together both jaws may be opened by operating their rods *f*, each jaw being held by spring *l'* in a fixed open position by its nose contacting with a stop *k* as shown in Fig. 3. 80

The nose of each jaw presses against the tail of the opposing jaw, and as the cars are brought together, the jaws are turned on their pivot *c* against springs *i* until their tails automatically latch themselves in 85 notches *j* in the latch levers as shown in Fig. 1 and the cars are coupled together. The same result may be accomplished by opening only one of the knuckle jaws, the other remaining closed. This case is illus- 90 trated in Fig. 2 wherein it is seen that when the couplers are brought together the nose of the closed jaw (on the right) will contact with the tail of the open jaw (on the left) and force the latter to turn into a position 95 to engage its latch lever.

Rod *h* is pivoted to the knuckle jaw at such a point that when the jaw is in its closed position spring *i* tends to hold it closed, yet when the latch lever is opened 100 a slight pull by the opposing coupler will throw the spring across the line connecting pivots *c* and *g* and spring *i* will act to press the jaw into its open position against stop *k*.

When the knuckle jaw is latched in its closed position any amount of pull by the opposing coupler cannot free its tail from

notch *j*, as the pull thereon is in a direction directly away from the pivot of lever *d*.

Spring *i* also insures that there shall be no shaking or jolting apart of the engaged members.

Having now fully described my invention, what I wish to claim and protect by Letters Patent is:

1. In a car coupling, in combination, a pivoted knuckle jaw provided with a tail, a pivoted latching lever adapted to engage said tail and means comprising a compression spring interposed between said jaw and lever tending to hold the jaw closed when it is in latched position and operating in connection with a pull on the jaw when the latching lever is moved to release the jaw, to turn and maintain said jaw fully open.

2. In a car coupling, in combination, a pivoted knuckle jaw provided with a tail, a pivoted latching lever adapted to engage said tail and means comprising a compression spring interposed between said jaw and lever tending to hold the jaw fully open, and operating when said jaw is turned toward its closed position to reverse its action and hold the jaw in locking relation with the latch lever, said spring being constantly under tension.

3. In a car coupling, in combination, a lever pivoted between its ends and having a rearwardly extending arm on one side of its pivot and an arm on the other side of its pivot, said lever being notched near its pivot, a pivoted jaw having a tail engaging

said notch when in closed position and thereby held from opening, and a tension device one end of which is carried by and movable with the second arm of the latch lever and the other end of which is carried by the jaw between its pivot and the engaging end of the tail.

4. In a car coupling, in combination, a lever pivoted between its ends and having a rearwardly extending arm on one side of its pivot and an arm on the other side of its pivot, said lever being notched near its pivot, a pivoted jaw having a tail engaging said notch when in closed position and thereby held from opening, and a tension device one end of which is carried by and movable with the second arm of the last lever and the other end of which is carried by the jaw between its pivot and the engaging end of the tail, and the point of connection of the tension device to the jaw, when closed, being at one side of, but relatively close to a line connecting the jaw's pivot and the point of connection of the tension device with the lever, whereby, when the jaw is moved away from its closed position by the manual turning of the latch lever, said point of connection of the tension device to the jaw moves on the other side of the line, causing the tension device to open said jaw fully.

In testimony of which invention, I have hereunto set my hand, at Westgrove, Pa., on this 29th day of May, 1916.

JAMES A. LARMORE.
